COLUMBIA PLANOGRAPH CO., WASHINGTON, D. C.

UNITED STATES PATENT OFFICE.

ELBY R. MILLS, OF SABINA, OHIO.

COMBINED GAS SUPPLY AND LIGHTING DEVICE.

1,095,512.

Specification of Letters Patent.

Patented May 5, 1914.

Application filed February 16, 1911. Serial No. 608,912.

To all whom it may concern:

Be it known that I, ELBY R. MILLS, a citizen of the United States, residing at Sabina, in the county of Clinton and State of Ohio, have invented certain new and useful Improvements in Combined Gas Supply and Lighting Devices, of which the following is a specification.

My invention relates to the improvement of combined gas supply and lighting devices, and has particular relation to devices of that class which are to be used in connection with automobile lighting.

The objects of my invention are to provide a simple, inexpensive and reliable mechanism by means of which a desirable quantity of gas under a predetermined pressure may be supplied to automobile or other lamps, the gas thus supplied being ignited through the operation of the gas controlling valve; to so construct my device as to provide improved means for adjusting the valve handle with relation to the valve stem and to otherwise produce an effective device of the class mentioned in which by a single operation of a controlling lever, a lamp or lamps may be supplied with a desirable quantity and pressure of gas and simultaneously ignited. These objects I accomplish in the manner illustrated in the accompanying drawings, in which—

Figure 1 is a central vertical section of my device, Fig. 2 is a view in elevation thereof at right angles with that shown in Fig. 1, and, Fig. 3 is a plan view.

Similar numerals refer to similar parts throughout the several views.

In carrying out my invention, I employ an upright valve casing body comprising lower and upper sections 1 and 2, the lower section having its upper portion vertically recessed to form a chamber 1^a and the upper portion of said chamber being normally closed by having threaded in connection therewith the lower externally threaded portion of the upper section 2. The connection of the members 2 and 1, is rendered further gas tight by the employment of a suitable gasket 3, which is interposed between a peripheral flange of the member 2 and the upper end of the member or section 1.

The lower end of the chamber 1^a is tapering or conical as shown and leading from the apex of the inverted cone-shaped recess thus formed, is a central downwardly extending gas port or passage 4, the lower end of the latter leading into the apex of the cone-shaped upper end of a similar gas chamber 5, which is provided in the lower portion of the section 1. This gas chamber 5 on one side, communicates with a laterally extending passage 6, which through the medium of a tube 7, is extended outward and suitably connected with a storage gas tank not herein shown. The tubular member 7 may be formed separately from the casing section 1 and screwed in connection therewith as shown, or it is obvious that the same may be cast with said casing section. The lower end of the casing section 1 is formed with a downwardly extending tubular and externally threaded neck 8, in which is rotatably mounted the stem of a vertical needle-point valve 9, the latter having a threaded connection with an opening in the lower part of the casing section 1 and having its conical valve termination adapted to seat in the conical upper end of the chamber 5 and to control the flow of gas through the passage 4. The casing neck extension 8 and a portion of the stem of the valve 9, is incased by a suitable packing nut 10, in which is provided about said valve stem, suitable packing 11.

Leading out of the chamber 1^a is a pipe section or tubular member 12 which may be connected in any suitable manner with the burners of one or more lamps. Extending downwardly through the reduced upward extension neck 2^a of the casing section 2, is a rotary valve stem 13, the threaded portion of said stem engaging internal threads in said member 2, while the lower portion of the stem is provided with the usual needle point valve termination 13^a, which is adapted to close or regulate the opening of the upper end of the port or passage 4. At the point of entrance of the valve stem 13 into the casing neck 2^a, I provide a stuffing box or packing nut 13^b adapted to prevent leakage of the gas about said stem. The upper end portion of the

stem 13 passes through a vertical opening which is formed through an operating lever or handle 14 toward one end of the latter. As indicated in the drawing, this end portion of the lever 14 is split vertically, the split thus formed and which is indicated at 14^a leading from the opening through which the stem 13 passes out through the end of the lever. On the outer side of the valve 10 stem 13, the portions of the lever which are separated by the split 14^a are connected by a transverse screw 15, the tightening or loosening of which regulates the frictional engagement of the lever or handle with said 15 valve stem.

Mounted on one side of the upper portion of the valve casing, is an upright insulating block or plate 16, which may be of any suitable non-conducting material. Connected 20 with the upper portion of this insulating plate is a suitable wire binding post 17, said insulator also having connected therewith an upwardly extending vertical contact plate or strip 18.

25 It will be readily understood that the volume and pressure of gas which may pass from the gas supply tank through the tubular member 7 and chamber 5, and thence through the port or passage 4, may be regulated by the position of the needle point valve 9, which may be so set with relation to the lower end of the port 4, as to admit of the passage of but a predetermined quantity of gas. In the drawing, I have shown 30 the controlling needle valve in its lowered or closed position, but it is obvious that when the valve 9 is properly opened and the valve 13 raised from its seat, the desired quantity of gas will flow through the chamber 5, the passage or port 4, chamber 1^a and tubular member 12 to the burners. It will be also observed that when the valve 13 is closed, the lever or handle 14 is so turned as to cause the contact extension 14^b of its 35 split end to extend in a direction parallel with the face of the strip 18. In the operation of opening the valve, however, the valve handle or lever is first given a quarter turn, resulting in the contact member 14^b coming 40 into contact with the strip or plate 18 in passing the same. It will thus be seen that in this quarter revolution of the handle, the valve 13 is not only opened sufficiently to permit a quantity of gas to pass to the 45 lamps, but an electrical contact is produced between the members 14^b and 18, which results in closing electric lighting circuits through a suitable arrangement of battery, coils and wires which lead to the lamp burners. As the movement of the handle is continued another quarter turn, it is obvious 50 that the production of the lighting sparks at the lamp burners, is discontinued and the

desirable quantity of additional gas supplied. 65

In view of the fact that I do not care to confine my invention to the exact method of wiring the parts hereof to produce the lighting spark, I have not illustrated or described the wiring system. It will be observed, 70 however, that the connection with the contact plate 18 is illustrated in Figs. 1 and 3 of the drawing, in which figures one of the conducting wires 19 is shown.

75 It will be readily understood that in the operation of my device, it is desirable that the operating handle or lever stands in a predetermined relation with the contact plate 18 when the valve 13 is closed, so that a predetermined quantity of gas will be 80 liberated from the passage 4 during the movement of said valve handle necessary to effect the spark producing contact of the members 14^b and 18. In view of the fact that this relative arrangement of parts 85 might be changed by the wearing of the valve termination 13^a of the needle point valve 13, I have provided means for changing the position or resetting the handle 14 on the stem 13, this means consisting in the 90 loosening of the screw 15 and tightening the same when the handle has been moved to its proper position.

95 From the construction and operation described, it will be observed that comparatively simple and inexpensive although positive means are provided for supplying gas burners with gas and igniting the same by one operation and although the construction described is particularly adapted for 100 use in the lighting of automobile lamps, it is obvious that the same may be applied to lamps used for other purposes.

105 While I have herein shown and described one particular embodiment of my invention, I wish it to be understood that I do not confine myself to all the precise details of construction set forth herein, as modification and variation may be made without departing from the spirit of the invention or exceeding the scope of the appended claims.

110 What I claim, is—

115 1. A fuel and ignition control comprising a stationary casing having communicating receiving and delivery chambers formed therein, an initial regulating valve in the receiving chamber to initially determine the supply of fuel thereto, a controlling valve in said delivery chamber regulable to vary the flow of gas to said chamber, and means effective by the operation of said last named valve to close an igniting circuit.

120 2. A fuel and ignition control comprising a stationary casing having communicating receiving and delivery chambers formed therein, an initial regulating valve in the re-

ceiving chamber to initially determine the supply of fuel thereto, a controlling valve in said delivery chamber and regulable to vary the flow of the gas out of said chamber, and regulable means operable upon the operation of said last named valve to close an igniting circuit.

In testimony whereof I affix my signature in presence of two witnesses.

ELBY R. MILLS.
